J. A. BASTIEN

REVOLVING GRATE AND FRAME FOR STEEL RANGES

Filed Dec. 9, 1922

Inventor

J. A. Bastien

By *Watson E. Colemann*
Attorney

UNITED STATES PATENT OFFICE.

JULES A. BASTIEN, OF GLOUCESTER, NEW JERSEY.

REVOLVING GRATE AND FRAME FOR STEEL RANGES.

Application filed December 9, 1922. Serial No. 605,853.

To all whom it may concern:

Be it known that I, JULES A. BASTIEN, a citizen of the United States, residing at Gloucester, in the county of Camden and State of New Jersey, have invented certain new and useful Improvements in Revolving Grates and Frames for Steel Ranges, of which the following is a specification, reference being had to the accompanying drawings.

This invention relates to certain improvements in stove grates and it is an object of the invention to provide a novel and improved device of this general character which can be employed with advantage in the shaking and raking of a fire bed.

Another object of the invention is to provide a novel and improved grate of this general character which can be conveniently operated in a manner to maintain the same in a position to facilitate the requisite draft through the fire bed and which also can be operated to facilitate the cleaning of the bed and the dumping of the fire bed.

The invention consists in the details of construction and in the combination and arrangement of the several parts of my improved stove grate whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in elevation of the lower portion of a stove showing the means associated with my improved grate for limiting the swinging or rocking movement thereof and to permit the dumping of the grate;

Figure 2 is an enlarged fragmentary sectional view taken substantially on the line 2—2 of Figure 1; and

Figure 3 is a sectional view taken substantially on the line 3—3 of Figure 2.

As disclosed in the accompanying drawings, A denotes the lower portion or ash pit of the stove structure above which is mounted the grate frame F.

An end of the frame F is provided with a depending bearing 1 with which is en-

gaged an end portion of the grate shaft or bar 2, the opposite end portion of said bar or shaft 2 being disposed through and operatively supported by a wall 3 of the stove structure. The portion of the shaft or bar 2 exterior of the stove structure is herein disclosed as angular in cross section at 4 to provide means whereby a suitable implement may be engaged therewith for rocking the shaft or bar 2.

Mounted upon the shaft or bar 2 at predetermined points spaced longitudinally thereof are the sleeves 5 from each of which radiate the arms 6, the outer arms being substantially longitudinally aligned with the third arm substantially at right angles thereto.

The outer extremities of the arms 6 are connected by the grate bars 7 each being substantially semi-circular in form. Interposed between the end bars 7 are the intermediate bars 8 also substantially arcuate in form. The adjacent extremities of the adjacent arms 7 and 8 are connected by the interposed webs or bars 9 as is also true in connection with the adjacent intermediate bars 8. The central portions of adjacent bars 7 and 8 and intermediate bars 8 are connected by interposed webs or bars 10.

Extending outwardly from the central portions of the bars 7 and 8 are the raking lugs 11 each of said lugs being pyramidal in form.

The extended portion of the shaft or bar 2 has radiating therefrom a rock arm 12 which normally has limited swinging movement between the stop shoulders 14 carried by the arm 15. The arm 15 is positioned exteriorly of the stove structure and has one end portion pivotally supported as at 16 for swinging movement toward or from the shaft or bar 2 while the opposite end portion of said arm 15 is normally engaged with a keeper 17 carried by the stove structure.

The bars 7 and 8 are of such length that the portions thereof between the intermediate arms 6 and an end arm 6 serve to closely approach and extend across the grate frame F and upon which the fire bed is supported. Should such portion of the grate become clogged or the efficiency thereof otherwise reduced, it is only necessary to rock the shaft or bar 2 sufficiently to position the opposite end portions of said bars 7 and 8 immediately adjacent to the frame F.

The arms of the bars 7 and 8 are also of

such length as to properly extend across the grate frame F when the shaft or bar 2 is rocked to shake the fire and during which operation the lugs 11 serve to rake the fire bed and particularly to break or reduce clinkers or the like which may be formed in the fire bed and which action is facilitated in connection with the longitudinal or side portions of the frame F. As is illustrated in the drawings it is also to be noted that the shaft or bore 2 is so positioned and the bars 7 and 8 are on such radii as to have portions of said bars at all times partially extending within the grate frame F and it is also to be noted that the bars 7 and 8 do not extend above the adjacent portion of said frame.

As is illustrated in Figure 2 of the drawings it is to be noted that the raking lugs 11 are of a length to extend above the frame F as the same pass or travel between the side members of the frame.

When it is desired to dump the fire it is only necessary to raise the arm 15 sufficiently to free the same from the arm 12 whereupon the grate will drop down.

To facilitate the requisite passage of the lugs 11 the under surface of the inner marginal portions of the side members of the frames is provided with an undercut groove or recess 18 for each of the lugs 11.

I also find it of advantage to provide the outer end of the arm 12 with the groove or channel 19 extending thereacross and which receives the inner marginal portion of the arm 15, when said arm 15 is in its normal or working position as illustrated in Figure 1 of the accompanying drawings.

From the foregoing description it is thought to be obvious that a stove grate constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

1 claim: —

In combination with a stove structure including a grate frame, the inner marginal portions of the side members of the grate frame being provided with undercut recesses, a grate underlying the frame and supported for rotary movement, said grate comprising a plurality of arcuate bars, outstanding lugs carried by the central portions of the bars, said lugs being adapted to pass through the recesses of the frame, and means for normally limiting the movement of the grate with respect to the frame, said bars having portions at all times extending partially within the frame but below the upper surface of the adjacent portions of the frame, the lugs being of a length to extend above the frame when moving between the side members of the frame.

In testimony whereof I hereunto affix my signature.

JULES A. BASTIEN.
